DRIVING MECHANISM

Romeo M. Nardone, East Orange, N. J., assignor
to Eclipse Aviation Corporation, East Orange,
N. J., a corporation of New Jersey

Application April 10, 1937, Serial No. 136,192

2 Claims. (Cl. 74—7)

My invention relates to driving mechanism, adapted for transmitting torque for various purposes such as the starting of internal combustion engines, more particularly but not necessarily airplane engines, and the object thereof is to provide a simple efficient and reliable apparatus of this character for either power or manual operation or both combined and characterized more particularly by novel and efficient construction whereby the power means and its operating connections may be rendered immune from the effects of rotation of the drive whenever induced by a rotation reversing force applied to the drive itself.

In Patent No. 1,753,830, granted to Raymond P. Lansing on April 8, 1930, there is disclosed a starting apparatus wherein the power means and its operating connections are automatically disengaged from the engine engaging section of the starter whenever there is manually induced rotation of the latter—but when the rotation of the latter is engine induced, as by an engine "back-fire" during cranking, there is no such disengagement; and under such circumstances, in the Lansing patent construction, the motor armature suffers an undesirable backward rotation, along with all the operating connections. The present invention, in contrast to that of the Lansing patent, renders the motor parts immune to rotation not only on such occasions but also on the occasions of manual cranking of the engine, and moreover, provides unitary means for achieving this double immunity.

These and other objects of the invention will become apparent from inspection of the following specification when read with reference to the accompanying drawing wherein is illustrated the preferred embodiment of the invention. It is to be expressly understood, however, that the drawing is for the purpose of illustration only, and is not designed as a definition of the limits of the invention, reference being had to the appended claims for this purpose.

In the drawing:—

Fig. 1 is a longitudinal sectional view of only that portion of a starting apparatus which needs illustration for an understanding of the manner of applying the present invention thereto;

Fig. 2 is a perspective view in elevation of one element of the unitary means for achieving the double immunity above described; and

Fig. 3 is another view in perspective of the complete unitary device above referred to.

As shown, the said unitary device is in the form of a dual overrunning clutch, with a roller sec-

tion and a ratchet section, the clutch assembly being interposed in the drive from a power shaft 10 to the engine cranking member 11, corresponding to the engine cranking "barrel" 2 in the Lansing Patent No. 1,753,830, above described; the manual driving means being shown as including a central shaft 12 and a driving gear 13 rotatable by a hand turned gear (not shown) engageable therewith, and preferably corresponding to that shown at 19 in the said Lansing patent.

The roller section of the clutch assembly, best shown in Fig. 3, comprises an outer race 16, rollers 17, and cam member 18. Cam 18 forms part of a driving pinion 19 which is splined or otherwise secured (as indicated at 21) to the above described shaft 12. The ratchet section of the clutch assembly shown in Fig. 2, includes a circular ring 22 secured to a long-face internal gear 23, but having axial movement with respect thereto, and having laterally disposed ratchet teeth 24 meshing with similar teeth formed on the lateral rim 26 of race 16. Spring 27 tends to keep the ratchet teeth 24, 26 in engagement during operation of shaft 12 as the driving means of the starter, but yields to permit free sliding of the teeth when shaft 10 is employed in lieu of shaft 12.

The drive is normally transmitted to the barrel 11 by way of shaft 10, bevel gears 31 and 32, pinions 33 and 34, outer clutch race 16, wedged rollers 17, inner race 18, pinion 19, and the two sets of planetaries 36 and 37. During this operation ratchet teeth 26 slide freely over teeth 24 the latter being held against rotation by the engagement of splines 25 with the teeth of the long-face stationary, or reaction gear 23. Ratchets 24 and 26 being engaged, should back-firing occur, the teeth 24, 26, will lock to prevent reverse rotation of member 16 and hence no reversal of rotation can be transmitted back to the planets 36 and 37, the gears 32 and 31, or the motor shaft 10. Likewise, in the event of operation of the starter by way of hand shaft 12 in lieu of motor shaft 10, the drive will include only the inner race 18 of the clutch, the rollers 17 idling within outer race 16, whereby rotation of the planets 36 and 37, gears 32 and 31 and shaft 10 is avoided.

What is claimed is:

1. In combination with a work performing drive, manually operated means connecting with said drive for actuation thereof, power means, and operating connections between said power means and said drive, said operating connections including an overrunning clutch having a flanged roller race rotatable only by said power means, a

series of teeth on the flange of said flanged roller race and means engageable with said teeth for rendering said power means immune from the effects of rotation of the drive whenever induced by a rotation reversing force applied to the drive itself.

5. 2. In an engine starter including a drive having an engine engaging member as a part thereof, manually operated means connecting with said drive for actuation thereof to crank the engine, power means for cranking the engine, and operable through the instrumentality of said drive,

and operating connections between said power means and said drive, said operating connections including an overrunning clutch having a flanged roller race rotatable only by said power means, a series of teeth on the flange of said flanged roller race and means engageable with said teeth for rendering said power means immune from the effects of rotation of the drive whenever induced by a backfire of the engine, said clutch also having a second roller race rotatable by either said manually operated means or said power means.

ROMEON M. NARDONE.
